UNITED STATES PATENT OFFICE

THOMAS H. HANRATTY, OF KARNS CITY, PENNSYLVANIA.

WELL-TUBING CATCHER.

1,160,073.

Specification of Letters Patent.

Patented Nov. 9, 1915.

Application filed December 29, 1914. Serial No. 879,553.

To all whom it may concern:

Be it known that I, THOMAS H. HANRATTY, a citizen of the United States, residing at Karns City, in the county of Butler and State of Pennsylvania, have invented new and useful Improvements in Well-Tubing Catchers, of which the following is a specification.

The invention relates to a well tubing catcher, and more particularly to the class of holding or locking devices for well tubing used in oil, gas, or water wells.

The primary object of the invention is the provision of a device of this character wherein the well tubing will be prevented when broken from falling to the bottom of the well, and will be supported in a manner to permit limited vibration thereof during the operation of the well.

Another object of the invention is the provision of a device of this character wherein the well tubing can be readily and easily removed from the well, as well as capable of being lowered to the desired points within the well.

Another object of the invention is the provision of a device of this character which is simple in construction, reliable and efficient in use, and inexpensive in manufacture and installation.

With these and other objects in view, the invention consists in the construction, combination and arrangement of parts as will be hereinafter fully described, illustrated in the accompanying drawing, and pointed out in the claims hereunto appended.

In the drawings:—Figure 1 is a fragmentary elevation of a well tubing showing the device, constructed in accordance with the invention, applied. Fig. 2 is a vertical longitudinal sectional view thereof. Fig. 3 is a sectional view on the line 3—3 of Fig. 1. Fig. 4 is a sectional view on the line 4—4 of Fig. 2. Fig. 5 is a sectional view on line 5—5 of Fig. 2.

Similar reference characters indicate corresponding parts throughout the several views in the drawing.

Referring to the drawing in detail, A designates the well, and B a portion of the well tubing having connected thereto near its lower end the catcher device C, hereinafter fully described.

The catcher device C comprises an inner tubular or cylindrical member 5 formed near one end thereof with an inverted L-

shaped slot 6, while formed near the opposite end therein is a transverse slot 7, the member 5 being arranged concentrically about the well tubing B and has rotatably fitted thereon an outer member 8 which is held against longitudinal displacement on the member 5 through the medium of a lug 9, which projects into and works within the transverse slot 7 in the said member 5, while threaded on the lowermost end of this member 5 is a collar 10 which forms a bearing for the member 8, while telescoped upon the upper end of the member 5 is an expanding head 11, the closed end 12 of which is apertured to receive the tubing B which is formed with spaced annular collars 13 disposed on opposite sides of the closed end 12 of the head so that the latter is connected thereto, between the collars 13, yet the pipe B is free for a vertical sliding movement through the head for a limited distance to allow for the vibration of the said pipe during the working of the well. The tubing B is formed exteriorly thereof with a longitudinal key 18 which engages in a keyway 19 formed in the closed end 12 of the head 11 so that on the turning of the tubing B the head 11 will turn therewith.

The member 8 is formed with a plurality of resilient spreader arms 14, which are adapted to be acted upon by the cone end 15 of the expander head 11 so that the same will be spread outwardly for engagement with the wall of the well A to hold the device therein for supporting the tubing B near its lower end, the member 8 being fitted on its outer face with outwardly bowed leaf springs 16 which serve to guide the device in the well A for the centering of the tubing B therein.

The expander head 11 carries a lug 17 which projects into and works within the inverted L-shaped slot 6, so that when the lug 17 is engaged in the horizontal branch of the said slot 6, the expander head 11 will not drop and spread arm 14 while device is being lowered into well, but guide springs 16 will keep device centered while allowing free movement in lowering or raising tubing.

After tubing catcher is lowered to proper position the tubing is rotated, member 8 being prevented from rotation by the frictional resistance of spring 16 against inner wall of well, member 11 rotating with tub-

ing by means of key 18 engaged in keyway 19 in closed end 12 of member 11. When member 11 rotates to point where lug 17 enters vertical portion of slot 6, it drops by 5 gravity throwing outwardly spreader arms 14 by means of wedge action of expanding head 11, thus locking tubing catcher firmly in position.

Should it be desired to remove tubing B 10 from well A all that is necessary to do is to pull tubing upward, the lower collar 13 engaging closed end 12 of expanding member 11, then releases arms 14.

From the foregoing description, taken in 15 connection with the accompanying drawing, it is thought that the construction and manner of use of the device will be clearly understood, and therefore a more extended explanation has been omitted.

20 What is claimed is:—

1. An apparatus of the class described comprising a tubular member having an inverted substantially L-shaped slot, a spreading element mounted for limited rotary movement upon the tubular member and having a plurality of grab jaws, and an expansion head mounted upon the tubular member having a lug to engage in the slot for guiding said head for rotary and slide- 25 able movement longitudinally on the tubular member for action upon the jaws to spread the same when the head is moved in one direction.

2. An apparatus of the class described 30 comprising a tubular member having an inverted substantially L-shaped slot, a spreading element mounted for limited rotary movement upon the tubular member and having a plurality of grab jaws, an expansion head mounted upon the tubular member having a lug to engage in the slot for guiding said head for rotary and slid- 35 able movement longitudinally on the tubular member for action upon the jaws to spread the same when the head is moved in one direction.

and means on the expansion head for locking the same when in one position.

3. An apparatus of the class described comprising a tubular member having an inverted substantially L-shaped slot, a spreading element mounted for limited rotary movement upon the tubular member and having a plurality of grab jaws, an expansion head mounted upon the tubular member having a lug to engage in the slot for guiding said head for rotary and slid- 50 able movement longitudinally on the tubular member for action upon the jaws to spread the same when the head is moved in one direction, means on the expansion head for locking the same when in one position, and resilient means on the spreading element for engagement in a well tubing to guide the said spreading element therein.

4. An apparatus of the class described 55 comprising a tubular member having an inverted substantially L-shaped slot, a spreading element mounted for limited rotary movement upon the tubular member and having a plurality of grab jaws, an expansion head mounted upon the tubular member having a lug to engage in the slot for guiding said head for rotary and slid- 60 able movement longitudinally on the tubular member for action upon the jaws to spread the same when the head is moved in one direction, means on the expansion head for locking the same when in one position, and resilient means on the spreading element for engagement in a well tubing to guide the said spreading element therein, and means on the tubular member for preventing displacement longitudinally of the spreading element thereon.

In testimony whereof I affix my signature in presence of two witnesses.

THOMAS H. HANRATTY.
